ELEVATED STORAGE TOWER

Jehu D. Paulson, 2705 Everett St., Raleigh, N.C.

Filed Sept. 29, 1959, Ser. No. 57,724

Term of patent 14 years

(Cl. D91—1)

FIGURE 1

The rear of the elevated storage tower is substantially like the front elevational view shown in FIGURE 1.

What I claim is:

The ornamental design for an elevated storage tower, as shown and described.
